This technical drawing illustrates a complex mechanical assembly, possibly a part of a typewriter. The drawing is labeled 'Fig. 2.' and shows a side view of the mechanism. Key components include a base plate (5) with a central slot (2), a vertical support (12) on the right, and a horizontal frame (11) on the left. Various mechanical parts are mounted on these frames, including a lever system (14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52) and a central spring mechanism (13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52).

UNITED STATES PATENT OFFICE.

WILLIAM CONNER, OF PHILADELPHIA, PENNSYLVANIA.

MACHINE FOR SEPARATING THE WHITES FROM THE YOLKS OF EGGS.

Application filed December 3, 1921. Serial No. 519,631.

The object of my invention is to provide a novel, simple and efficient machine for thoroughly and expeditiously separating the whites from the yolks of eggs; and with this object in view the invention consists in the novel construction, combination and arrangement of parts hereinafter described and claimed.

In the accompanying drawings illustrating the invention.

Figure 1 is a side view of a machine embodying my invention.

Figure 2 is a top view thereof.

Figure 3 is a transverse section of the machine on line 3—3 of Figure 1.

Figure 4 is a top view of the inclined troughs and adjuncts.

Referring to the drawings, the frame of the machine includes two end standards 2 and 4 having parallel bars 5 and 6 secured on the upper ends thereof. The bars 5 and 6 are rigidly connected by a bar 7 and two pairs of bars 8, 8 and 9, 9 which extend longitudinally of the machine and are connected to the transverse bars 5 and 6.

The bars 8, 8 are shaped in cross section to form a trough 10 which is inclined, as shown in Figure 1, and which is adapted to receive the whites and unbroken yolks of eggs; and the bars 9, 9 are shaped in cross section to form a receiver 11 for the whites and accidentally broken yolks of eggs, as will be hereinafter described, the receiver 11 is in the form of a trough which is inclined and which extends adjacent and parallel to the trough 10.

The bars 8, 8 and 9, 9, forming the troughs may be formed of polished metal or glass or other suitable material through which the whites and yolks of eggs will slide downwardly by gravity after being deposited into the upper end portions of the troughs; and the sides of the end portions of the bars 8, 8 and 9, 9 are embraced by parts of the bars 5 and 6 and secured thereto by set screws 12.

The standard 2 is provided with two spaced, outwardly-extending brackets 13, and extending between and secured to these brackets 13 are the end portions of a shaft 14 which extends transversely of the machine. The shaft 14 carries a cup 15 which has a block or bearing 16 formed on the bottom thereof through which the shaft 14 extends. The cup 15 is adapted to receive the contents of an egg shell when the egg

is broken by hand and the white and yolk thereof permitted to drop into the cup; and the cup is provided with a suitable spout 17 through which the white and yolk of the egg may be discharged when the cup 15 is tilted by turning it about the axis of the shaft 14. The cup 15 is movable longitudinally of the shaft 14 to bring its spout into registry with the upper end of either trough 10 or 11, in a position above the same, so that the contents of the cup may be discharged into either trough by tilting the cup after its spout has been brought into registry with the trough which is to receive its contents, as will be hereinafter explained. The shaft 14 is provided with suitable fixed, stop collars 18 between which the bearing block 16 of the cup 15 is moved and which limit its movement longitudinally of the shaft and ensure the proper registry of the spout 17 with the troughs 10, and 11.

The cup 15 is held normally in the horizontal position, shown by full lines in Figure 1, by two helical springs 19 which extend through openings in the block 16 on the respective sides of the shaft 14 in parallel relation thereto, the ends of the springs 19 being secured to the brackets 13. The bearing block 16 is adapted to slide over the springs 19 when the cup 15 is moved longitudinally of the shaft 14 and the springs hold the cup in its normal or horizontal position, and automatically return it thereto after it has been tilted therefrom and released.

One of the brackets 13 has an upwardly extending arm 20 secured thereto and provided with an end portion 21 extending horizontally over the cup 15 when its spout is over the trough 10. The end portion 21 of the arm 20 has a knife like upper edge against which the eggs may be struck by hand to split their shells to permit the contents thereof to be dropped into the receiving cup 15.

The bottom of the receiver or trough 11 is closed, and the bottom of the trough 10 has a longitudinal slot 22 therein formed between the bars 8, 8. The slot 22 is tapered, growing narrower from the upper end of the trough 10 toward the lower end thereof, as shown in Figure 2, and the lower end of the slot 22 terminates in a relatively large opening 23 which extends vertically through the walls of the trough 10. The

slot 22 is of a width to permit the white of an egg to pass downwardly therethrough and to prevent the unbroken yolk of an egg from passing therethrough, and the opening 23 is large enough to permit the yolk of an egg to pass downwardly through the same. The width of the slot 22 at the lower end portion thereof may be varied by adjusting the lower end of the outer bar 8 toward or from the lower end of the inner bar 8, and for this purpose I provide a suitable hand operated adjusting screw 24 mounted to turn in a bearing 25 on the bar 6 and screwed into a block 26 which is slidable on the bar 6 and secured to the trough bar 8. When the screw 24 is turned, the threads thereof working in the block 26 will move the lower end of the outer bar 8 toward or from the lower end of the inner bar 8, in accordance with the direction in which the screw 24 is turned, longitudinal movement of the screw 24 being prevented by collars thereon engaging the respective sides of the bearing 25.

The transverse bars 5 and 6 have opposing guideways 27 formed therein to which the end portions of a plate 28 are slidably fitted. The plate 28 is adapted to be moved transversely of the machine in the guideways 27 and it carries three inclined troughs 29, 30 and 31. The trough 29 is connected to the plate 28 by brackets 32, the trough 30 is connected to the trough 29 by brackets 33, and the trough 31 is connected to the trough 29 by a bracket 34, the whole forming an integral structure adapted to be moved as a unit when the plate 28 is moved.

The troughs 30 and 31 are arranged in alignment with and spaced from each other, and the trough 29 is arranged adjacent and parallel to the troughs 30 and 31. When the plate 28 and troughs carried thereby are in the normal position, as shown in the drawings, the trough 30 is directly beneath the slot 22 and the trough 31 is directly beneath the opening 23; and the plate 28 is adapted to be moved transversely of the machine to move the troughs 30 and 31 from beneath the slot 22 and opening 23 and to move the trough 29 to a position beneath the slot 22 and opening 23, and I shall now describe the devices for effecting this movement of the troughs.

Mounted to turn in bearings 35 on the frame bar 7 is a rockable shaft 36 provided with an upwardly extending handle 37 by means of which it may be rocked by hand. The shaft 36 is also provided with downwardly extending arms 38 which are connected by links 39 to brackets 40 secured to and projecting downwardly from the plate 28 near the respective ends thereof, whereby, when the shaft 36 is rocked back and forth, the plate 28 and troughs carried thereby will be moved back and forth transversely of the machine. Helical springs 41 connect the

lower ends of the arms 38 to screws 42 on the machine frame and tend to move the plate 28 and troughs carried thereby away from their normal position to move the troughs 30 and 31 from beneath the slot 22 and opening 23, and to move the trough 29 to a position beneath said slot and opening. The plate 28 and its troughs are held normally in the position shown in the drawings, against the action of the springs 41 by a latch device comprising a hook 43 on one of the arms 38 engaging a hook 44 on the lower end of a reciprocative rod 45 mounted to slide up and down in a bearing 46 on the end of the frame bar 5. The hook 44 is adapted to be raised into engagement with the hook 43 by a spring 47 encircling the rod 45 between the bearing 46 and a head 48 on the upper end of the rod. When it is desired to move the trough 29 to position beneath the slot 22 and opening 23, it is merely necessary to depress the rod 45 by hand, thereby releasing the hook 44 and permitting the springs 41 to shift the plate 28 and its troughs instantly and bring the trough 29 to the position beneath the slot 22 and opening 23. Thereafter, when it is desired to return the plate 28 and its troughs to the normal position, the shaft 36 is rocked by means of the handle 37 against the action of the springs 41 to move the parts back to normal position, and the hook 44 is re-engaged with the hook 43.

The trough 30, in its normal position, extends longitudinally of the machine and beneath the slot 22 from beneath the upper end of the trough 10, and the trough 30 terminates before reaching the trough 31 or a position beneath the opening 23, and the trough 30 diverges downwardly from the trough 10 to support the white of an egg at progressively increasing distances from the trough 10, as the white of an egg descends by gravity through the same.

Secured to the bottom of the bars 8 is a cutting device comprising a pair of flat blades 49 which lap each other and have opposing, diverging cutting edges 50 adapted to receive the white of an egg between them for severing the same, as will be hereinafter explained. The blades 49 are secured to the bottom of the bars 8 by screws 51 extending through longitudinal slots 52 in the blades. The slots 52 permit the blades 49 to be adjusted toward and from a position above the lower end of the trough 30 and to be adjusted to vary the angle of their cutting edges 50.

The operation of the machine is as follows:

The parts rest normally in the positions shown in the drawings, and the person operating the machine breaks or splits the shell of an egg against the blade or arm 21 and the contents of the shell is dropped into the

receiving cup 15 and the broken and emptied shell is thrown into any suitable, conveniently located receiver. If it appears upon observation that the yolk within the 5 cup 15 is unbroken, the cup is tilted by hand to the dot-and-dash line position shown in Figure 1, and the white and the yolk of the egg are thereby discharged from the cup 15 into the upper end of the trough 10. The 10 cup 15 is then released, permitting the springs 19 to return it to its normal, horizontal position, and the person operating the machine breaks the shell of another egg against the blade and discharges the white 15 and yolk thereof into the receiving cup 15, and, if the yolk is unbroken the cup is again tilted to discharge its contents into the upper end of the trough 10, and so on the eggs are successively broken, the contents 20 of their shells dropped into the receiving cup 15, observed, and discharged into the upper end of the trough 10, so long as the yolks of the successive eggs are unbroken. When, however, a broken yolk appears within 25 in the cup 15, the cup is shifted on the shaft 14 to bring its spout 17 over the upper end of the trough or receiver 11 and the contents of the cup or the broken yolk and white of the same egg are discharged into the trough 30 11, and this occurs each time a broken yolk appears within the cup 15.

The broken yolks and their accompanying whites slide down within the trough 11 by gravity and are discharged from the lower 35 end thereof into a suitable receptacle set beneath the same to receive them. The cup 15 is cleansed before it receives the contents of another egg shell.

When the whites and yolks are discharged 40 into the trough 10 they move downwardly therethrough, and almost immediately upon being received by the trough 10 the bulk or large portions of the whites descend by gravity down through the wide upper end 45 portion of the slot 22 and are received within and supported by the upper end portion of the trough 30 with parts of the whites extending through the slot 22 and adhering to their yolks which remain within 50 the trough because the slot 22 is too narrow to permit them to pass therethrough. In this condition, the whites and yolks slide by gravity down toward the lower ends of the troughs 10 and 30, the yolks supported by 55 the trough 10 and the bulk or large body portions of the whites supported by the trough 30 at progressively increasing distances from the yolks, gradually stretching and thinning the stems of the whites which 60 continue to adhere to the yolks and extend through the slot 22. At or about the time that the bulks or bodies of the whites reach and fall from the lower end of the trough 30, the thin stems extending therefrom to their yolks engage the cutting edges 50 of the blades 49 which sever the stems near their yolks. This done, the whites fall from the lower end of the trough 30 into a suitable receptacle placed beneath the same to receive them, and the yolks fall through the 70 opening 23 from the trough 10 to the trough 31; and as the lower end of the trough 31 is adjacent to the lower end of the trough 29, the yolks fall from the trough 31 into the same receptacle placed beneath the trough 29 to receive the whites and broken yolks therefrom as previously explained, said receptacle also extending beneath the trough 31.

In the use of the separated whites and 80 yolks, it makes little or no difference whether the receptacle for the yolks receives some of the whites in addition to the yolks, but it is highly desirable that extremely little or no part of any of the yolks shall reach the trough 30 or the receptacle placed beneath the same to receive the whites. Therefore if after a white and its unbroken yolk have been discharged from the receiving cup 15 into the trough 10, the yolk 90 should be accidentally broken by the quick separation of the white therefrom before the white reaches the cutting edges 50, or from any other cause, the person operating the machine, upon observing the broken yolk within the trough 10, will quickly depress the rod 45 and thereby free the plate 28 and permit the springs 41 to shift the plate 28 and troughs carried thereby, instantly, to move the troughs 30 and 31 from beneath the trough 10 and move the trough 29 into a position beneath the trough 10, so that the accidentally broken yolk will be received within the trough 29, through 95 which it will pass by gravity and be discharged into the receptacle for the yolks, the receptacle for the yolks being beneath the lower end of the trough 29 in all positions thereof. As the shifting movement of the troughs 29, 30 and 31 is very slight, the 100 lower end of the trough 30 always remains over the receptacle for the whites to insure the discharge of all of the whites into the same.

Should a bad yolk and white of an egg, 105 unfit for use, appear within the receiving cup 15 the cup is tilted to raise its spout 17 and thereby discharge its contents from its side opposite to its spout and into a suitable receptacle placed beneath the same to receive the discarded eggs. Thereafter the cup 15 is cleansed before it receives the contents of another egg shell.

Before any whites and yolks are 110 discharged into the troughs 10 and 11 the surfaces of all troughs are moistened by wiping them with a wet cloth or sponge to lubricate the same so that the whites and yolks 115 will slide freely therethrough, and thereafter the whites and yolks keep the surfaces 120

125

130

135

over which they slide supplied with sufficient lubricant from their own moisture.

I claim as my invention—

1. In a machine for separating the whites from the yolks of eggs, the combination of a trough having a longitudinal slot of gradually lessening width in the bottom thereof, and means for supporting the trough in an inclined position, said slot being of a width to permit the passage therethrough of the white of an egg and to prevent the passage of the unbroken yolk of an egg.

2. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and means beneath said trough to support the white of an egg extending through said slot prior to its complete separation from the yolk the last named means limiting the movement of the white of an egg from said slot.

3. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and an inclined trough beneath the first named trough to support the white of an egg extending through said slot prior to its complete separation from the yolk.

4. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and an inclined trough beneath the first named trough to support the white of an egg extending through said slot prior to its complete separation from the yolk, the second named trough diverging downwardly from the first named trough.

5. In a machine for separating the whites from the yolks of eggs, the combination of a trough having a slot in the bottom thereof, and means below said trough and spaced from said slot for severing the white of an egg extending through the slot from a yolk within the yolk.

6. In a machine for separating the whites from the yolks of eggs, the combination of a trough having a slot in the bottom thereof, a support beneath said trough for the white of an egg extending through said slot from a yolk within the trough, and means be-

tween and spaced from the trough and said support for severing the white of an egg extending between them.

7. In a machine for separating the whites from the yolks of eggs, the combination of a trough having a slot in the bottom thereof, means below said trough for supporting at gradually increasing distances therefrom the body of the white of an egg extending through the slot from a yolk within the trough, and means between said trough and the first named means for severing the white of an egg extending between them.

8. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and means below and spaced from said trough for severing the white of an egg extending through the slot from a yolk within the trough.

9. In a machine for separating the whites from the yolks of eggs, the combination of a trough having a longitudinal slot of gradually lessening width in the bottom thereof, means for supporting the trough in an inclined position, said slot being of a width to permit the passage therethrough of the white of an egg and to prevent the passage of the unbroken yolk of an egg, and means below the narrow end portion of the slot for severing the white of an egg extending through the slot from a yolk within the trough.

10. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, means beneath said trough to support the white of an egg extending through said slot prior to its complete separation from the yolk, the last named means limiting the movement of the white of an egg from said slot, and means below said trough for severing the white of an egg extending through the slot from a yolk within the trough.

11. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, an inclined trough beneath the first named trough to support the white of an egg extending through said slot prior to its complete separation from the yolk, and

- means below and spaced from said trough for severing the white of an egg extending through the slot from a yolk within the trough.
- 5 12. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, an inclined trough beneath the first named trough to support the white of an egg extending through said slot prior to its complete separation from the yolk, and means below said trough for severing the white of an egg extending through the slot from a yolk within the trough, the second named trough diverging downwardly from and in the same general direction as the first named trough.
- 10 13. In a machine for separating the whites from the yolks or eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and a knife supported below and spaced from the trough and having a cutting edge in the path of the white of an egg depending through and below the slot from a yolk moving downwardly through the trough.
- 15 14. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and a cutting device below the trough and having diverging cutting edges adapted to receive between them and sever the white of an egg depending through and below the slot from a yolk moving downwardly through the trough.
- 20 15. In a machine of the character described, the combination of a supporting frame, means to receive and separate the white and yolk of an egg, a receptacle for receiving the white and yolk of an egg prior to the separation thereof, said receptacle being tiltable from a normal position to discharge its contents into said means, and means to return the receptacle to its normal position after being tilted and released.
- 25 16. In a machine of the character described, the combination of a supporting frame, means to receive and separate the white and yolk of an egg, a receptacle for receiving the white and yolk of an egg prior to the separation thereof, and a receiver for receiving the whites and accidentally broken yolks of eggs, said receptacle being movable longitudinally of the shaft to positions adjacent
- receiving the whites and accidentally broken yolks of eggs, said receptacle being movable to discharge its contents into either said means or said receiver.
- 30 17. In a machine of the character described, the combination of a supporting frame, means to receive and separate the white and yolk of an egg, a shaft, a receptacle on said shaft for receiving the white and yolk of an egg prior to the separation thereof, and a receiver for receiving the whites and accidentally broken yolks of eggs, said receptacle being movable longitudinally of the shaft to positions adjacent to said means and adjacent to said receiver, and said receptacle being movable about the axis of the shaft from a normal position to discharge its contents into either said means or said receiver.
- 35 18. In a machine of the character described, the combination of a supporting frame, means to receive and separate the white and yolk of an egg, a shaft, a receptacle on said shaft for receiving the white and yolk of an egg prior to the separation thereof, a receiver for receiving the whites and accidentally broken yolks of eggs, said receptacle being movable longitudinally of the shaft to positions adjacent to said means and adjacent to said receiver, said receptacle being movable about the axis of the shaft from a normal position to discharge its contents into either said means or said receiver, and means to return the receptacle to said normal position after being moved therefrom and released.
- 40 19. In a machine of the character described, the combination of a supporting frame, means to receive and separate the white and yolk of an egg, a shaft, a receptacle on said shaft for receiving the white and yolk of an egg prior to the separation thereof, a receiver for receiving the whites and accidentally broken yolks of eggs, said receptacle being movable longitudinally of the shaft to positions adjacent to said means and adjacent to said receiver, said receptacle being movable about the axis of the shaft from a normal position to discharge its contents into either said means or said receiver, and a spring holding the receptacle in said normal position and serving as a means to return the receptacle to its normal position after being moved therefrom and released.
- 45 20. In a machine of the character described, the combination of a supporting frame, means to receive and separate the white and yolk of an egg, a shaft, a receptacle on said shaft for receiving the white and yolk of an egg prior to the separation thereof, a receiver for receiving the whites and accidentally broken yolks of eggs, said receptacle being movable longitudinally of the shaft to positions adjacent

to said means and adjacent to said receiver, said receptacle being movable about the axis of the shaft from a normal position to discharge its contents into either said means or said receiver, and a spring holding the receptacle in said normal position and serving as a means to return the receptacle to its normal position after being moved therefrom and released, said spring extending parallel to said shaft and through an opening in the receptacle, and the receptacle being slidably fitted to the spring.

21. In a machine for separating the whites from the yolks of eggs, the combination of a trough having a slot in the bottom thereof, and a receiver for accidentally broken yolks movable to a receiving position beneath the slot from a normal position away from said receiving position.

22. In a machine for separating the whites from the yolks of eggs, the combination of a trough having a slot in the bottom thereof, a receiver for accidentally broken yolks movable to a receiving position beneath the slot from a normal position away from said receiving position, means to hold the receiver in the normal position and adapted to be operated to release the same, and means to automatically move the receiver to the receiving position when released.

23. In a machine for separating the whites from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, and an inclined receiving trough for accidentally broken yolks movable to a receiving position beneath the slot from a normal position away from said receiving position.

24. In a machine for separating the whites

from the yolks of eggs, the combination of a trough having a longitudinal slot in the bottom thereof, means for supporting the trough in an inclined position, said slot being of a width to permit the passage therethrough of the white of an egg and to prevent the passage of the unbroken yolk of an egg, an inclined receiving trough for accidentally broken yolks movable to a receiving position beneath the slot from a normal position away from said receiving position, means to hold said receiving trough in the normal position and adapted to be operated to release the same, and means to automatically move the receiver to the receiving position when released.

25. In a machine for separating the whites from the yolks of eggs, the combination of a trough having a slot in the bottom thereof, means to return the receptacle to its normal position after being tilted and released, a spring tending to move the receiver to the receiving position, and a latch device adapted to hold the receiver in the normal position and to be operated to release the same.

26. In a safety egg breaking device, the combination with a stand; of a hopper stop fixed to the top thereof; a horizontal hopper pivot bar extending above and in front of the stop; a hopper open at the front and top pivoted at the bottom on a line in front of its center on the pivot bar.

27. In a safety egg breaking device, the combination with a stand; of a hopper stop fixed to the top thereof; a horizontal hopper pivot bar extending above and in front of the stop; a hopper open at the front and top pivoted at the bottom on a line in front of its center on the pivot bar; and a breaker bar across the hopper over the stop.

In testimony whereof I affix my signature hereto.

WILLIAM CONNER.
